UNITED STATES PATENT OFFICE.

FREDERICK SCHLICH AND ADRIAN FEYH, OF NEW YORK, N. Y.

IMPROVEMENT IN BOTTLE-FILLING APPARATUS.

Specification forming part of Letters Patent No. 138,534, dated May 6, 1873; application filed July 11, 1872.

To all whom it may concern:

Be it known that we, FREDERICK SCHLICH and ADRIAN FEYH, of the city and State of New York, have invented an Improvement in Bottle-Filling Apparatus, and the following is declared to be a correct description of the same.

The object of this invention is to provide a means for filling a number of bottles at once with beer or similar liquids. The material to be bottled is generally contained in open tanks or vats, and into this the uncorked bottle is inserted by hand, so as to allow the liquid to fill the bottle. It is then removed for corking. As but three or four bottles can be handled in this way at once the operation consumes considerable time when a large number of bottles are to be filled. Our invention consists in a frame or stand for holding a number of bottles so that they can all be inserted in the tank at once for filling, and the bottles can be readily removed from the frames and replaced by empty ones, and the filling operation is thus proceeded with very rapidly.

In the drawing, Figure 1 is a plan, and Fig. 2 is a vertical section, of said apparatus.

The frame is made of strips of metal that will not corrode by the action of the liquid. The strips *a b* and cross-strip *c* form the bottom. These strips are bent up to form the sides, and are riveted at their ends to the strip *d*, forming the rim of the frame. The handles *e* are provided at the ends of the frame for lifting it. The bottles *f* are placed in this frame in an upright position, and to prevent

their floating when first inserted into the liquid we provide the wire frame *i* for holding the bottles down. This is placed over the bottles and rests upon their necks, and is just above the tops of the handles *e*. The divisions of the frame *i* being smaller than the diameter of the bottles the frame *i* is held in a convenient position, so that as the handles are grasped by the hands the thumb can be placed upon the frame *i* to prevent the bottles lifting, and the frame and bottles can then be inserted into the liquid to be bottled, and held there until the bottles are full. When the bottles are full they are lifted out of the tank, the wire frame *i* removed, and the bottles taken out and empty ones put in. The frame *i* is then replaced and the filling operation proceeds rapidly.

The frame may be made of a size to hold any desired number of bottles. We have shown a frame containing six, but, generally, two dozen is the most convenient number.

We claim as our invention—

A bottle-filling apparatus, consisting of a frame or stand for holding the bottles, combined with a movable wire frame for keeping the bottles in place and handles for lifting the stand, located so that the operator can simultaneously hold down the frame *i*, as set forth.

Signed by us this 1st day of July, 1872.

FREDERICK SCHLICH.

ADRIAN FEYH.
